UNITED STATES PATENT OFFICE.

JACOB A. MEINHARDT, OF CHICAGO, ILLINOIS.

MOP FRAME AND HANDLE COUPLING.

1,422,368.

Specification of Letters Patent. Patented July 11, 1922.

Original application filed June 13, 1921, Serial No. 477,268. Divided and this application filed December 19, 1921. Serial No. 523,352.

To all whom it may concern:

Be it known that I, JACOB A. MEINHARDT, a citizen of the United States, residing at Chicago, in the county of Cook and State of Illinois, have invented certain new and useful Improvements in a Mop Frame and Handle Coupling, of which the following is a specification.

My present invention relates to mops, and this application is a division of my application for Letters Patent for improvements in a mop and supporting frame therefor, filed June 13, 1921, and bearing Serial Number 477,268, now pending in the United States Patent Office.

The present invention has particular relation to a coupling or bearing connection between the handle and frame of a mop, and has for one of its objects, to provide such a device whereby the mop frame and the handle connected thereto by means of my improved coupling or bearing connection will self-adjustingly position themselves with respect to each other in its operation, without undue looseness of said members.

Another object of the invention is to provide a coupling of the above mentioned character, or bearing connection between the handle and the frame of a mop which is simple in construction, easily applied and will removably and pivotally support the handle.

A still further object is to provide a coupling wherein one of the members thereof may be formed or stamped from a single piece of metal.

Other objects and advantages of the invention will be disclosed in the following description and explanation.

In the accompanying drawing which serves to illustrate an embodiment of the invention—

Fig. 1 is a plan view of a mop frame showing a portion of the handle therefor mounted thereon by means of my improved connection or coupling.

Fig. 2 is a central sectional view taken on line 2—2 of Fig. 1 looking in the direction indicated by the arrows.

Fig. 3 is an enlarged plan view of a fragment of a mop frame and a portion of the handle therefor showing the connection or coupling uniting said handle and frame, and

Fig. 4 is an end elevation of Fig. 3 viewed from the front end of the device.

Like numerals of reference refer to corresponding parts throughout the different views of the drawing.

In the accompanying drawing, I have shown a portion of a mop head mounted on the frame, of the construction set forth in my aforesaid pending application, but it will be understood that said mop head forms no part of the present invention as it is covered by claims in my said pending application.

Referring now more particularly to Fig. 1 of the drawing, the reference numeral 5 designates as a whole the frame of the device, which may be of my suitable shape or outline, but by preference substantially triangular as shown, and is made of a single piece in the form of a rod or large wire. The sides 6 of the frame 5 are arranged at angles to each other and at their junctures form a more or less pointed portion of the frame for the purpose of entering corners to be cleaned. One of the sides 6 is provided with an inwardly extended arm 7 which terminates short of the axial line of the frame 80 as is clearly shown in Fig. 1, while the other arm 6 of the frame is provided with an inwardly extended arm 8 which is located in the same plane with the sides and extension 7, but is extended first toward the side 6 with which it is connected as at 8^a, and then towards the other side of the frame, thereby providing a shaft or arm 9 upon which the bearing connection or coupling for the handle of the device is mounted.

The shaft portion of the arm 8 is screw-threaded as shown, and has loosely mounted thereon a sleeve or collar 10 which is of sufficient length to fit snugly between the prongs 11 of a socket member 12 which is preferably tubular in shape and may be provided on its inner surface with a plurality of pitched or inclined ribs 13 to coact with the screw-threads 14 of the handle 15 which is removably fitted into said socket member. 100 As shown, the prongs of this member are extended therefrom in parallelism and each is provided with a transverse opening for the reception of the shaft 9. Located on the outer surface of each of the prongs 11 and around the shaft, is a washer 16 and located on the outer surface of each of said washers is a split spring washer 17 which

are held in place against the washers 16 by means of nuts 18 one of which is located in screw engagement with the shaft 9 outwardly of each of the spring washers 17.

5 In assembling the parts of this bearing connection or coupling which unites the shaft 9 and handle 15, one of the nuts 18 is placed on the free end of the shaft 9 and screwed thereon to about the position adjacent 10 cent the arm 8 as shown in Fig. 1, after which one of the spring washers or members 17 and one of the plain washers 16 is positioned on the shaft 9 against the inner surface of said nut. The prongs 11 of the 15 socket member 12 having located therebetween the sleeve 10, are then placed on the shaft 9 so that one end of said prongs will rest against the washer 16 adjacent the arm 8 of the frame. When thus positioned 20 the other members 16 and 17 are positioned on the outer portion of the shaft 9 and held in position thereon by the nut 18 adjacent the free end of said shaft. By this arrangement it is apparent that by turning the nuts 25 18 in the proper direction the tension of the spring members 17 can be regulated so as to increase or decrease the pressure of the prongs 11 of the socket 12 against the ends of the sleeve 10, thereby affording means for 30 holding the socket 12 against too free movement on the shaft 9, yet so as to permit of its self-adjustment with respect to the frame 5 while the device is being used.

As it is desirable that the plain washers 35 16 should be held against rotation on the shaft 9, the said shaft is provided with a flattened surface 19 and the washers 16 are formed with openings of a shape to correspond with the cross-sectional form or shape 40 of the shaft on which they are mounted.

By reference to Figs. 3 and 4 of the drawings, it will be seen and understood that the socket member 12 is made of a single piece of metal, which piece is bent longitudinally 45 between its side edges, thereby bringing the said edges together, in which position they

are held by means of a laterally extended tongue 20 integral with one of said edges, and a recess 21 in the other edge, with which said tongue engages. By thus bending the socket member 12, it is manifest that the prongs 11 thereof will be spaced in parallelism with one another so that the openings in said prongs will coincide or align for the reception of the shaft 9 of the mop frame. The sides of the socket 12 are curved transversely as shown, and form, when united at their edges, a cylindrical socket for the lower or front end of the handle. 60

Having thus fully described my invention, what I claim as new and desire to secure by Letters Patent is—

1. In a device of the class described, the combination with a screw-threaded shaft, of a socket member for a handle having at one of its ends a pair of spaced prongs provided with apertures for said shaft, a sleeve located between said prongs around the shaft, a washer located on the outer side of each of said prongs around the shaft and against rotation thereon, a split spring washer located around the shaft against the outer surface of each of the first named washers, and nuts engaging said shaft and located against the outer side of each of said spring washers. 65

2. In a device of the class described, the combination with a handle, of a frame having a screw-threaded shaft, a socket member 80 for receiving said handle at one end of said member and pivotally mounted at its other end on the shaft, a washer located around the shaft on each side of the pivot point of the socket member and fixed against rotation on the shaft, a split spring washer located around the shaft against the outer surface of each of the first named washers, and nuts engaging said shaft and located against the outer side of each of said spring 85 washers. 90

JACOB A. MEINHARDT.
